UNITED STATES PATENT OFFICE.

ARNOLD KREUSLER, OF NEW YORK, N. Y.

PROCESS OF UTILIZING LIQUEFIED GASES.

SPECIFICATION forming part of Letters Patent No. 660,755, dated October 30, 1900.

Application filed November 4, 1899. Serial No. 735,761. (No specimens.)

To all whom it may concern:

Be it known that I, ARNOLD KREUSLER, a citizen of the United States, residing at New York, (Kreischerville,) borough of Richmond, 5 county of Richmond, State of New York, have invented certain new and useful Improvements in Processes of Utilizing Liquefied Gases, of which the following is a specification.

10 My invention relates to a process for utilizing liquefied gases and the like, and has for its object to produce a structure in which such gases, and especially liquefied air, can be employed to advantage.

15 My invention consists in a process for utilizing gases and the like, an example of which will be fully set forth and the characteristic features of the invention claimed.

In the drawing forming part hereof I have 20 illustrated a form of apparatus for carrying out my invention. This apparatus is shown in sectional elevation and is in some degree diagrammatic and illustrative.

In the drawing, *a* is a suitable tank or reservoir, herein shown as open at the top and adapted to contain liquefied gases.

b is a stand-pipe which forms part of the liquid-circulating system hereinafter mentioned. The liquefied-gas reservoir communicates with the stand-pipe *b* by pipe *c*, provided with a suitable valve or valves *d* and preferably with an injection-nozzle *e*. The stand-pipe *b* may be provided with a dome *f* and forms part of a circulatory system which 30 is likewise comprised in part by a pipe *g*, preferably provided with a suitable valve *h*. The pipe *g* communicates with the interior of the stand-pipe *b*, near the top thereof, passes through the furnace or heater *i* in a coil *h*, 35 and thence extends to the lower part of the stand-pipe *b*. A pipe *j* extends from the dome *f* of the stand-pipe *b* to carry off the gases for use. The liquefied gas is pumped from the reservoir *a* to the stand-pipe *b* 40 through the pipe *c* by the pump *k*, whose cylinder *l* is provided with a motive fluid through

the pipe *m*, which communicates with the dome *f* of the stand-pipe *b*.

The operation of the device is as follows: Liquid air or other liquefied gas is placed in a 50 reservoir *a* and a suitable liquid is placed in the liquid-circulating system, standing about up to the height shown in the stand-pipe. The liquefied gas is pumped from the reservoir *a* to the stand-pipe *b*, passing through the nozzle *e*, the said gas upon striking the heated liquid in *b* expanding rapidly, thereby cooling the said liquid in its ascent therethrough, the products of expansion—to wit, the gas—bubbling up through the liquid into the dome 55 *f* and passing out of the pipe *j*, part of the said gas being operative through the pipe *m* to work the pump. The rush of the expanding gas up the stand-pipe *g* causes a circulation of liquid, the hot liquid pouring into the 60 stand-pipe *b* and the cold liquid flowing into the coil *h*, where it is heated, there being thus supplied a constant circulation of heated liquid. By regulating the heat of the liquid-circulating system the temperature of the 65 expanded gas may be regulated, and thus the 70 gas may be used for refrigerating and other purposes.

Having described my invention, what I claim, and desire to secure by Letters Patent, 75 is—

The herein-described process of vaporizing liquid air to produce a gas-pressure which consists in leading the said liquefied air into physical contact with a body of liquid in a 80 circulatory system whereby the said liquid air will be expanded into gaseous form and will bubble through said liquid and initiate a circulation thereof, and heating a part of the said circulatory system extraneous to the 85 body of liquid through which the gas passes substantially as specified.

ARNOLD KREUSLER.
